W. E. HARVEY

RESERVE FUEL VALVE

Filed July 31, 1924

FIG. 1.

FIG. 2.

FIG. 3.

Inventor:

W. E. HARVEY,

By Monroe E. Miller

Attorney.

UNITED STATES PATENT OFFICE.

WALTER E. HARVEY, OF MERIDIAN, MISSISSIPPI.

RESERVE-FUEL VALVE.

Application filed July 31, 1924. Serial No. 729,394.

To all whom it may concern:

Be it known that I, WALTER E. HARVEY, a citizen of the United States, residing at Meridian, in the county of Lauderdale and 5 State of Mississippi, have invented certain new and useful Improvements in Reserve-Fuel Valves, of which the following is a specification, reference being had therein to the accompanying drawing.

10 The present invention relates to reserve supply devices for use with liquid tanks for keeping a partial supply of the liquid in reserve, and it is the primary object of the invention to provide a novel and improved 15 reserve valve construction for tanks wherein the liquid is drawn up through the top of the tank.

The device is intended especially for use in the gasoline or fuel tanks of automobiles 20 for holding in reserve a quantity of fuel in the tank, so that when the main supply is exhausted, a sufficient quantity will be held in reserve, to enable the automobile to proceed to a garage or service station for replenishing the supply of fuel in the tank, thereby avoiding the annoyance and inconvenience resulting from the entire exhausting 25 of the fuel at a distance from a source of supply.

30 The device, however, can be used for other purposes also.

Another object is the provision of a reserve valve structure comprising a novel assemblage and construction of the component 35 elements, whereby the device is practical, serviceable and efficient in use.

With the foregoing and other objects in view, which will be apparent as the description proceeds, the invention resides in the 40 construction and arrangement of parts, as hereinafter described and claimed, it being understood that changes can be made within the scope of what is claimed, without departing from the spirit of the invention.

45 The invention is illustrated in the accompanying drawing, wherein—

Figure 1 is a view, partly in side eleva-

tion and partly in section, of the device as positioned in the tank.

50 Fig. 2 is a vertical median section of the upper portion of the device taken on the line 2—2 of Fig. 3.

Fig. 3 is a horizontal section on the line 55 3—3 of Fig. 1.

Fig. 4 is a horizontal section on the line 4—4 of Fig. 1.

A chambered head or casing 11 is provided to be secured on the top of the tank 12, and has a depending boss 13 to extend 60 through an opening in the top of the tank, said head 11 being soldered or otherwise secured on the tank. The head 11 has a tubular extension 14 at one side for the connection of the tubing or conduit through 65 which the liquid is pumped or drawn from the tank, the passage of said extension communicating with the chamber of the head. A bonnet 15 is screw-threaded within the upper portion of the head 7 to close the 70 chamber, and a plug or bushing 16 is screw-threaded within the bottom of the head, the bottom of the head and boss 13 having a screw-threaded opening to receive said plug or bushing. The bushing has a flange 75 17 to seat on the bottom of the head and an upstanding boss 18 of angular outline for the engagement of a wrench for turning the bushing in applying and removing it. When the bonnet 15 is removed, the 80 bushing 16 can be unscrewed and removed upwardly from the head.

Vertical concentric tubes 19 and 20 are disposed within the tank, and the outer tube 19 extends upwardly through and is 85 soldered or otherwise secured to the bushing 16 so that the tube 19 is carried by the bushing as a unitary part therewith. The tube 19 extends above the boss 18 to the bonnet 15, and is provided between its 90 upper end and the bushing with an arcuate slot 21. A nipple 22 is engaged in the inner tube 20 and is disposed within the slot 21. Said nipple serves three purposes. First, it provides a port establishing communication between the chamber of the 95

head and the passage of the tube 20; second, it limits the longitudinal movement of the tube 20 in the tube 19; and third, the nipple provides a stop to limit the turning movement of the tube 20.

The inner tube 20 extends upwardly through a central opening in the bonnet 15, and said bonnet has an upstanding boss 23 through which the tube 20 extends. A stem 10 24 is secured within the upper terminal of the tube 20 for receiving a handle 25, which is secured on the stem and tube by means of a nut 26 threaded on the stem, although other securing means for the handle can be used. The stem 24 also closes or plugs the upper end of the tube 20.

A gland or packing nut 27 is screw-threaded on the boss 23 and contains packing surrounding the tube 20, to prevent leakage through the bonnet 15 along the tube 20.

The tubes 19 and 20 extend close to the bottom of the tank, and a member 28 is fitted over the lower terminal of the tube 19 and is soldered or otherwise secured to said tube. 25 The member 28 has the opposite ports 29 and 30 which extend through the tube 19 also, as seen in Fig. 4, and the member 28 has a passage or tubular extension 31 extending upwardly from the port 30 to a desired distance or height above the bottom of the tank. The tube 20 has the ports 32 to 30 register alternately with the ports 29 and 30 for establishing communication between the tank and the tube 20.

Ordinarily, the handle 25 is turned to normal position, as seen in Figs. 1 and 2, with the nipple 22 contacting with one end of the slot 21, to bring one port 32 into registration with the port 30, so that the tube 20 communicates with the interior of the tank by way of the upwardly extending passage 31. The liquid from the tank therefore flows down through the passage 31 and ports 30 and 32 into the tube 20, from which it flows 45 through the nipple 22 and extension 14 into the tube or conduit which carries the liquid off, the liquid being drawn from the tank by a pump or by a vacuum tank such as used in automobiles. Should the level of the liquid in the tank fall to the upper end of the passage 31, without the tank having been refilled, the liquid in the tank below the upper end of the passage 31 cannot pass out, and is therefore held in reserve for an emergency of this kind, especially when a warning is desired that the liquid in the tank is nearly exhausted. The flow of liquid from the tank will therefore stop. Then, by turning the handle 25, the tube 20 is turned to 55 bring one port 32 into registration with the port 29 which opens into the tank lower down than the upper end of the passages 31. Accordingly, the reserve quantity of liquid in the tank can be drawn therefrom through 60 the port 29 and tube 20, thereby permitting 65 a limited supply of liquid to be used until the tank can again be filled.

The device can be readily taken apart for purpose of cleaning, repair or replacement. Thus, by removing the handle 25, the bonnet 15 can be unscrewed from the head 11 and removed. Then, by unscrewing the bushing or plug 16 from the head 11, the tubes 19 and 20 are readily lifted with the bushing and withdrawn from the tank, the member 28 being carried by the tube 19 and passing through the opening in the head 11. The head 11 is the only part which is secured to the tank permanently, and the removal of the parts of the device does not disturb the connection of the tube or pipe with the extension 14.

Having thus described the invention, what is claimed as new is:

1. A valve structure of the character described including a head having a chamber and an outlet, concentric tubes having ports to register with one another for controlling the flow through the inner tube, said tubes entering said chamber, the outer tube having a slot in said chamber, a nipple carried by the inner tube in said slot to limit the relative movement of the tubes and to establish communication between said chamber and inner tube, and means for moving one of 95 said tubes.

2. A valve structure of the character described comprising a head having a chamber and an outlet, concentric tubes having ports to register with one another, said tubes entering said chamber, the outer tube being connected with the head so as not to turn normally, means for moving the inner tube to move the ports into and out of registration, the outer tube having a slot in said 105 chamber, and a nipple carried by the inner tube within said slot to limit the movement of the inner tube and to establish communication between the inner tube and chamber.

3. A valve structure of the character described comprising a head, a removable bonnet secured to the head, a removable bushing secured within the head, said head having a chamber and an outlet between said bonnet and bushing, concentric tubes having 115 ports to register with one another, the outer tube extending through and being secured to the bushing, the inner tube having a portion extending through the bonnet and provided with means for moving the inner tube, 120 the outer tube having a slot between the bonnet and bushing, and a nipple carried by the inner tube within said slot to limit the movement of the inner tube and to establish communication between the inner tube and said chamber.

4. A valve structure of the character described comprising a head having a chamber and an outlet, a removable bushing secured down within the bottom portion of the head, 130

a removable bonnet secured on the head, vertical concentric tubes having ports near their lower ends adapted to register with one another, the outer tube extending through and being secured to said bushing, the inner tube having a portion extending upwardly through the bonnet and provided with means for turning the inner tube, the outer tube having an arcuate slot between

the bonnet and bushing, and a nipple carried by the inner tube within said slot to limit the turning movement of the inner tube and to establish communication between said inner tube and chamber. 10

In testimony whereof I hereunto affix my 15
signature.

WALTER E. HARVEY.
